UNITED STATES PATENT OFFICE

132,314

DESIGN FOR A COMBINATION CAKE PAN AND DOUGH CUTTER

Russell V. Melville, Henning, Minn.

Application September 11, 1941, Serial No. 103,299

Term of patent 7 years

To all whom it may concern:

Be it known that I, Russell V. Melville, a citizen of the United States, residing at Henning, in the county of Otter Tail and State of Minnesota, have invented a new, original, and ornamental Design for a Combination Cake Pan and Dough Cutter, of which the following is a specification, reference being had to the accompanying drawing, forming a part thereof.

Figure 1 is a perspective view of a combination

cake pan and dough cutter, showing my new design;

Figure 2 is a perspective view of the same in assembled relation; and

Figure 3 is a cross sectional view, taken on the line 3—3 of Figure 2.

I claim:

The ornamental design for a combination cake pan and dough cutter, as shown.

RUSSELL V. MELVILLE.
